UNITED STATES PATENT OFFICE

MALICHI F. DEAN, OF TALLADEGA, ALABAMA

DESIGN FOR A SIGN FOR VEHICLES

Application filed December 5, 1930. Serial No. 37,899. Term of patent 3½ years.

To all whom it may concern:

Be it known that I, MALICHI F. DEAN, a citizen of the United States, residing at Talladega, in the county of Talladega and State of Alabama, have invented a new, original, and ornamental Design for a Sign for Vehicles, of which the following is a specification, reference being had to the accompanying drawings, forming part thereof.

Fig. 1 is a plan view of the sign for vehicles, and

Fig. 2 is a sectional view taken on the line 2—2 of Fig. 1.

I claim:

The ornamental design for a sign for vehicles, as shown.

MALICHI F. DEAN.
